CONTAINER HOLDER

Filed Jan. 9, 1928

INVENTOR:
Frederick M. Furey,
BY

Fred M. Furey

ATTORNEY.

UNITED STATES PATENT OFFICE

FREDERICK M. FUREY, OF LOS ANGELES, CALIFORNIA

CONTAINER HOLDER

Application filed January 9, 1928. Serial No. 245,593.

This invention relates to container holders, and in its present embodiment consists of a device for holding a tooth-paste tube so that it is normally supported with its mouth up, but may be inverted so that the paste may be conveniently applied to a tooth-brush.

My invention is useful for supporting various other types of containers such as bottles, and I therefore do not wish my invention to be construed as limited to the particular embodiment which is presented in this application.

One object of my invention is to provide a container support of the character mentioned in which the jaws are adjustable so that various sizes of containers may be supported.

It is another object of my invention to provide a container support in which the jaws are thread-shaped so that the threaded neck of a container (such as a tooth-paste tube) may be readily supported.

Another object of my invention is to provide a container holder of the character mentioned which includes a device supported on a stem, this device being extendible so that the tube may be inverted into dispensing position.

Another object of the invention is to provide a container holder designed for use in bank so that one of the containers may be extended and inverted without being interfered with by the other containers of the bank.

It is a further object of the invention to provide a container support which has a cover adapted to close the top of the container, this cover being positioned so that it is automatically closed when the container is moved into a retracted position under the support means.

Other objects and advantages of the invention will be pointed out in the following description.

Referring to the accompanying drawing in which the invention is illustrated:

Fig. 1 is a perspective view.

Fig. 2 is an elevational view.

Fig. 3 is an enlarged view showing the container in extended and inverted position.

Fig. 4 is an elevational view showing the

tube in extended position and the manner in which the cover is forced into closing position.

Fig. 5 is a front elevational view of the container holder.

Fig. 6 is a plan view of the container holder.

Fig. 7 is an enlarged fragmentary view of one of the jaws of the container holder.

Fig. 8 is a diagrammatic view illustrating the use of the invention in bank.

Referring to the drawing in detail, the holder has a support in the form of a horizontal stem 11, the outer end of which has a stop in the form of a head 12. The support shown is in the form of a screw which is screwed into the wall 13, as shown. The support 11 is adapted to slidably and rotatably carry a container holder device 15. This device has a cylindrical portion 16 which provides a sleeve, this sleeve surrounding the stem 11. Extending downward from the cylindrical portion 16 is a connecting portion 17. Extending forwardly and horizontally from the connecting portion 17 are jaws 19 which are formed by folding the two ends of the metal strip from which the device is formed on substantially a 45° angle. The arms 19 are arranged in vertical planes and the ends thereof are twisted into horizontal planes so as to provide jaws 20. The inner edges of the jaws 20 are V-shaped, as indicated at 21, and are beveled so as to provide engaging edges 22. As illustrated in Fig. 7 the points 23 provided by the forming of the V in the jaws may be twisted so that the jaws will have thread-shaped engaging edges 22.

The jaws are adjusted by means of an adjustment screw 25 which extends through one of the arms 19 and is threaded into the other of the jaws 19, there being a head 26 on one end thereof whereby the jaws may be moved together or apart. Carried by the adjustment member 25 is a cover 27 which is adapted to swing between closed and open positions. The cover 27 is made quite heavy so as to be weighted and is provided with a depression 28 into which the mouth of the container may extend. When the invention is used for tooth-paste tubes or other contain-

ers holding a chemically active substance, I prefer to make the cover 27 of lead so that there will be no corrosion. If desired, the adjustment member 25 may support a hook 5 29 on which a tooth-brush, indicated by dotted lines 30 of Fig. 1, may be supported.

In the drawing the container holder is supporting a container in the form of a tube 33, which in this illustration of the invention is 10 a tooth-paste tube. This tube 33 has a threaded neck 34 onto which the tooth-paste tube cover is screwed. When the tube 33 is placed in the holder of the invention, the tooth paste tube cover is removed and the jaws of the 15 device 15 are spread apart by operating the adjustment screw 25. The neck 34 of the tube 33 is then inserted between the jaws and the jaws are clamped together. Since the edges 22 are thread-shaped, the jaws will 20 engage in the threads 36 formed on the mouth 34.

When the device is in retracted position, as shown in Fig. 2, the tube 33 rests under the support 11 and the cover 27 is in closing position. To dispense tooth-paste from the tube 33 the device is moved outward on the support 11 so that it rests in the position shown in Fig. 1. The user then takes hold of the tube 33, preferably the lower end thereof and 30 swings this tube and the device 15 into inverted position, as shown in Fig. 3. The cover 27 due to its own weight at this time moves into open position, as shown. The user may then place the tooth-brush under the mouth 34 of the tube 33 and upon a squeezing of the tube 33 tooth-paste will be dispensed upon the brush. When the tube 33 is released, it will swing into the position shown in Fig. 1, but the cover 27 will be opened as indicated by 40 dotted lines 37. The tube 33 in the device is then moved from extended into retracted position, as shown in Fig. 2. When this is done, the cover 27 is engaged by the head 12 of the support 11, as indicated in Fig. 4, and is 45 forced into closed position.

In Fig. 8 the invention is illustrated when used in bank. A series of container holders are placed side by side and support containers 50 33. When it is desired to use one of them it is moved into extended position and inverted, as indicated at 40. It will be seen that when the container 33 is in extended position it is moved outward beyond the other container supports and containers so that it may be swung into and from inverted position without any interference to its operation.

I claim as my invention:

1. A container holder comprising: a holding device having a support; a cylindrical portion slidable on said support; and a pair of jaws associated with said holding device for gripping said container, said jaws being below said support when said holding device is in retracted position and extending beyond

the end of said support when said holding device is in extended position.

2. A container holder comprising: a support; a container holding device slidable on said support from retracted into extended position and being invertible; and a pair of jaws pivotally connected with said holding device for gripping said container, said jaws being below said support when said device is in retracted position and extending beyond 70 the end of said support when said device is in extended position.

3. A container holder comprising: a support; a container holding device having a cylindrical portion slidable on said support; and a pair of adjustable jaws associated with said device and having thread-shaped ends 80 adapted to grip the neck of said container, said jaws being below said support when said device is in retracted position and extending beyond 85 the end of said support when said device is in extended position.

4. A container holder comprising: a support; a container holding device slidable on said support from retracted into extended positions and being invertible; a pair of jaws on said device having thread-shaped ends adapted to grip the threaded outlet end of said container; and a cover for said container hingedly mounted on said device and adapted to be moved from open into closed position by said support when said device is moved from extended into retracted position.

5. A combination as defined in claim 1 in which a cover for said container is hinged to said holding device and is moved from open into closed position but being engaged by said support when said holding device is moved from extended into retracted position.

In testimony whereof, I have hereunto set my hand at Los Angeles, California, this 16th day of December, 1927.

FREDERICK M. FUREY.

CERTIFICATE OF CORRECTION.

Patent No. 1,757,184.

Granted May 6, 1930, to

FREDERICK M. FUREY.

It is hereby certified that error appears in the printed specification of the above numbered patent requiring correction as follows: Page 2, lines 59 and 60, claim 1, strike out the words "a holding device having" and insert the same before the article "a" second occurrence in line 60, same claim; and that the said Letters Patent should be read with these corrections therein that the same may conform to the record of the case in the Patent Office.

Signed and sealed this 24th day of June, A. D. 1930.

(Seal)

**M. J. Moore,
Acting Commissioner of Patents.**
